SAFETY RAZOR HANDLE

Louis V. Nigro, Saugus, Mass., assignor to The Gillette Company, Boston, Mass., a corporation of Massachusetts

Filed Aug. 17, 1961, Ser. No. 66,384

Term of patent 14 years

(Cl. D22—3)

FIG. 1

FIG. 3

FIG. 1 is a front elevational view, on an enlarged scale, of a safety razor handle embodying my new design,

FIG. 2 is a top plan view; and

FIG. 3 is a bottom plan view thereof.

The star ornamentation on the handle shown in FIG. 1 continues around the handle.

I claim:

The ornamental design for a safety razor handle, substantially as shown and described.
